UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Original application filed March 24, 1924, Serial No. 701,594. Divided and this application filed December 27, 1927. Serial No. 242,716.

This invention relates to controlling mechanisms, and more particularly to a check for the controller whereby the movement of the operating handle is limited. This application is a division of my copending application Ser. No. 701,594, filed March 24, 1924 for controlling mechanisms. The type of electric controller disclosed in said copending application is particularly adapted, although not exclusively, to be used in a mining machine.

Among the objects of the present invention is the provision of improved means for insuring the correct operation of an electric controller. A further object is to provide an improved manual means for insuring the proper operation of the operating handle of an electric controller. A further object is to provide an improved check for use in connection with a reversible type of electric controller. A still further object is to provide improved means to prevent the operating handle from being swung directly from the forward position to the reverse position. Other objects and advantages of the invention will subsequently appear.

In the accompanying drawings in which, for purposes of illustration, one embodiment which the invention may assume in practice is shown:

Fig. 1 is an elevational view of the controller handle together with the manual means for limiting movement thereof.

Fig. 2 is a vertical transverse sectional view taken through a portion of an electric controller of the drum type, my improved manual check being provided to cooperate with its operating handle.

Fig. 3 is a detail view of the controller check.

My copending application discloses an improved electric controller carried within a recess in a mining machine. A bearing member 3 is shown carried by a vertical plate 5, which is suitably secured to the mining machine.

The drum 7 is rotatably mounted within the bearing member 3 as by a shaft 8. This shaft extends through the drum 7 and is supported by a second bearing member (not shown) at its lower end, similar to bearing member 3, and likewise carried by the vertical plate 5. Beveled gear segment 9 is fixed to the shaft 8 adjacent the bearing member 3, and an actuating gear segment 10 meshes therewith. The

gear segment 10 is fixed to a shaft 11 rotatably carried by a cover 12, which is in turn fixed to the mining machine by bolts 13. Fixed to the shaft 11 is an actuating handle 14 whereby the gear segments may be oscillated.

Suitable means are provided for preventing continuous movement of this handle so as to rotate the drum 7 from one extreme position to the opposite extreme position. It is well known that to quickly reverse the current from "full forward" to "full reverse" is an abuse of the motor. The check means which I have herein described is adapted to temporarily halt the swing of the controller handle 14 at such position as to completely interrupt the current. This check cooperates with an arm 15 extending upwardly from the handle 14. The arm 15 carries a pin 16 which projects from the back side thereof. My improved check comprises a member 18 which is pivoted about a pin 19, the latter being in axial alignment with the pin 16 when arm 14 is in neutral position. The member 18 is provided with fingers 17 forming a U slot into which the pin 16 projects when arm 14 is in its neutral position. It will be seen from Fig. 2 that lugs 20 extend downwardly and upwardly from the member 18 in a plane to the rear of the fingers 17 and are provided for the purpose of engaging a stop pin 21. A grasping portion 22 projects from the body portion of the member 18.

In describing the operation of my improved device, let it be assumed that the controller handle 14 is in "full forward" position. When the operator desires to completely reverse the current, the controller handle 14 is moved until further movement is stopped by the engagement of pin 16 in the U slot formed by fingers 17. The controller handle 14 is now in neutral position and no current is passing through the controller. The operator thereupon grasps portion 22 and moves the member 18 to its opposite position. The controller handle 14 is now free to rotate the drum 7 so as to direct current to the motor in a reverse direction. It will be noted that when the operator desires to move the controller handle 14 from a given "reverse" position to any given "forward" position, the handle 14 is permitted to move only to neutral position where the pin 16 engages the U slot formed by fingers 17. The operator must now re-

verse the position of member 18 before the handle 14 is free to move to the desired "forward" position.

It is thus apparent that my improved device very effectively prevents movement of the controller handle from forward position to reverse position by a continuous movement. It also prevents movement from a reverse position to a forward position by continuous movement. The short interval during which the handle 14 must remain in neutral position insures the safety of the motor from abuse due to sudden reversal of the current.

While I have in this application specifically described one form which my invention may assume in practice, it will be understood that this form of the same is used for purposes of illustration and that the invention may be modified and embodied in various other forms without departing from its spirit or the scope of the appended claims.

What I claim as new and desire to secure by Letters Patent is:

1. In a motor reverse control, the combination with a controller lever adapted to swing in either direction from a central position, of a pivoted check member having a recess coaxial with its pivot, and an opening extending radially out of said recess.
2. In a motor reverse control, the combination with a controller lever adapted to swing in either direction from a central position and having a projection, of a member pivoted coaxially with said projection when the latter is in central position, said member having a recess coaxial with its pivot and an opening extending radially out of said recess.
3. In a motor reverse control, the combination with a controller lever adapted to swing in either direction from a central position and having a projection, of a check member having a lateral recess adapted to receive said projection, said check member being pivotally mounted at the central position to obstruct the movement of said projection so that the projection can not pass the central position without pivotal movement of the check member with the projection disposed in said recess.
4. In a motor reverse control, the combination with a controller lever adapted to

swing in either direction from a central position and having a projection, of a check member pivoted on an axis passing through said projection when at its central position, said check member affording a recess having a portion disposed on said axis of pivoting and adapted to receive said projection.

5. In a motor reverse control, the combination with a controller lever adapted to swing in either direction from a central position and having a projection, of a check member having a lateral U-shaped recess adapted to receive said projection, said check member being pivotally mounted on an axis passing through said projection when at its central position, the bottom of said recess being disposed on said axis.

6. In a motor reverse control, the combination with a manual operating member for the control adapted to move in either direction from a central position, said operating member having a projection, of a single pivoted check member movable into one position to obstruct movement of said manual operating member in one direction from said central position and movable into an opposite position to obstruct movement of said manual operating member in the opposite direction from said central position, said check member having a recess adapted to receive said projection and to contain the same during movement of said check member from one of said positions to the other.

7. In a motor reverse control, the combination with a manual operating member for the control having a projection, said manual operating member being mounted for movement in either direction from a central position, of a check member having a single recess into which said projection is adapted to project, said check member cooperating with said projection when the latter is in central position and being pivotally mounted to receive the centrally positioned projection into said recess when in one position and movable into an opposite position to free said projection for movement on past said central position.

In testimony whereof I affix my signature.

CHARLES W. WYMAN.
